(57) **CLAIM**

The ornamental design for a "trailer body," as shown and described.

DESCRIPTION

The petitioner was issued design patent D544,407 S on Jun. 12, 2007 and design patent D546,245 S on Jul. 10, 2007 for two related trailer bodies.

FIG. 1 is a perspective view of a trailer body showing my new design

FIG. 2 is a front elevation view thereof;

FIG. 3 is a rear elevation view hereof; and,

FIG. 4 is a top plan view thereof.

In the drawings, the broken lines in depict portions of the design that form no part of the claim.

My trailer body is characterized by a rounded lower frontal area which slopes backward and upward, a side-to-side arched top, a modified hour glass front and rear profile, fenders which flare outward and upward from the front of the trailer and extend to its rear, and a full width tail gate.
